VALVE SEAT GRINDING MACHINE

Frans O. Albertson, Sioux City, Iowa, assignor to
 Albertson & Company, Inc., Sioux City, Iowa,
 a corporation of Iowa

Application February 19, 1934, Serial No. 711,848

13 Claims. (Cl. 51—241)

The present invention relates to valve seat grinding machines particularly adapted for use in the forming, reconstruction or repair of valve seats of internal combustion engines. However, the methods and apparatus are of general application and may be utilized for valves of different kinds and for other grinding operations, and I do not wish to be limited to the particular use of my invention disclosed therein.

Valve grinding machines of the prior art may be classified into machines of the full contact type in which the stone is in contact with the working surface to be ground throughout the entire periphery of the stone, and single contact machines in which the stone is so tilted that it contacts only one side of the valve, or the stone may be arranged eccentrically with respect to the axis of revolution.

The devices of the prior art have, however, been very complicated, requiring either a complicated mechanism for rotating and revolving the stone, or requiring a ball bearing tool holder for supporting the stone, and the devices of the prior art have not been able to grind the valves with a suitable finish.

The difficulty with the full seat contact grinding wheels of the prior art was that this resulted in clogging or loading of the wheel with the cuttings or material ground from the seat, and this caused a change in the contour of the stone and resulted in the grooving of the valve seat. All the devices of the prior art were also very expensive on account of the complicated mechanism required and on account of the apparent necessity for using anti-friction bearings, and such devices could not be brought within the means of the ordinary garage owners, who could not afford expensive mechanism and make a profit on the work to be done.

One of the objects of the present invention is the provision of an improved method of reconstructing or grinding valve seats, by means of which the extremely hard seats of stellite, tungsten steel, or other hardened alloys can be ground quickly and uniformly to produce a finished seat, with a minimum amount of labor.

The tendency in the construction of valve seats for internal combustion engines is toward the use of seats of harder material, and it is one of the objects of the invention to provide an improved apparatus which is capable of working such hard seats more satisfactorily than could be done with the devices of the prior art.

Another object of the invention is to provide an improved method and apparatus which is adapt-

ed to produce a finished valve seat of predetermined angularity and adapted to eliminate the hand-lapping operation which was found necessary with grinding machines of the prior art.

Another object of the invention is the provision of an improved grinding tool of the full seat contact type which is adapted to eliminate the clogging and loading of the grinding wheel or the grooving of the seat, and to provide a grinding tool which is self-cleaning.

Another object of the invention is the provision of an improved grinding wheel adapted to disperse the cuttings continuously and to prevent loading of the wheel or filling with the cuttings of the interstices between the abrasive particles of the wheel at the surface, the cuttings being dispersed by a current of air and centrifugal force, at the periphery of the wheel when the wheel is lifted periodically from the seat.

Another object of the invention is the provision of an improved method and apparatus which is adapted to disperse the cuttings by means of a vibratory movement of the stone either in a vertical direction on the pilot or angularly in a lateral direction by means of the flexibility of the pilot, so as to prevent loading of the wheel and grooving of the seat and to produce a finished surface on the valve.

Another object of the invention is the provision of an improved tool assembly, including a motor driver and a universal connection between the motor driver and the grinding wheel, including means for eliminating detrimental shocks on the grinding wheel, but adapted to produce a dual action of grinding and dispersion of the cuttings by means of a single grinding wheel located for full contact with the seat.

Other objects and advantages of the invention will be apparent from the following description and from the accompanying drawings, in which similar characters of reference indicate similar parts throughout the several views.

Referring to the drawings,

Fig. 1 is a side elevational view of the grinding apparatus with a valve stem and valve stem guide in vertical section on a plane passing through the axis of the guide, the assembly including the motor driver, tool holder, grinding wheel and pilot;

Fig. 2 is a vertical sectional view, taken on a plane passing through the axis of the pilot, with the tool holder and grinding wheel in section, and the pilot in elevation;

Fig. 3 is a fragmentary enlarged sectional view of the connection between the motor driver and

the tool holder for the purpose of illustrating the vibratory or impulse action of the drive shaft on the tool holder which results in the dual action of the grinding wheel and dispersion of the cuttings, as well as smooth grinding;

Fig. 4 is a fragmentary sectional view of the lower end of the motor driver, shown in section for the purpose of illustrating the mechanism of the driver adapted to bring about this dual action;

Fig. 5 is a transverse sectional view taken on the plane of the line 5—5 of Fig. 4, showing the structure of one of the springs for resiliently supporting the drive shaft for axial movement;

Fig. 6 is another sectional view taken on the plane of the line 6—6 of Fig. 4 through the non-circular driving portion of the shaft and its socket in the tool holder;

Fig. 7 is another sectional view showing the tool holder spring in plan, the section being taken on the plane of the line 7—7 of Fig. 4, looking in the direction of the arrows;

Fig. 8 is an elevational view of a modified grinder assembly, in which the same pilot and tool holder are employed, with a flexible drive shaft, and the ordinary drill motor, having a suitable clutch;

Fig. 9 is a side elevational view of the flexible shaft employed in the device of Fig. 8.

Referring to Fig. 1, the complete assembly of the grinding apparatus preferably includes the motor driver 20, a tool holder 21, a grinding wheel 22, and a pilot stem 23.

The apparatus is illustrated in connection with a valve seat consisting of a hardened metal ring 24, which has been fixedly secured in the block 25 of an internal combustion engine having a valve seat guide 26.

The pilot 23 is preferably of the type having a lower cylindrical part 27 which fits the substantially cylindrical part of the valve stem guide 26 very closely, within one thousandth of an inch, for the purpose of centering the pilot 23 in the guide and locating it axially of the guide.

The pilot is also preferably provided with a very gradually tapered portion 28 which extends down into the upper part of the valve stem guide 26 and may be fixedly wedged in the guide by merely shoving the pilot downward. The taper is preferably about twenty-three thousandths of an inch per foot, and constitutes the sole means of securing, but any suitable taper may be used which will effect the wedging action and secure the pilot.

Another type of pilot which may be used is the expanding pilot shown in my prior Patent No. 1,902,207, issued March 21, 1933.

Referring to Fig. 4, the electric motor driver 20 is shown in detail in this figure. The motor driver preferably consists of an electric motor of the series wound type having a casing 29, within which is supported, by a plurality of screw bolts 30, the fixed field 31.

Any such suitable type of motor may be used, and therefore the details of construction of the motor will not be described.

The armature 32 is supported upon an armature shaft 33 and is preferably provided with a fan 34, also supported upon the armature shaft 33, by means of a hub 35 at the enlargement 36. A key 37 in a suitable key-way in the hub 35 and enlargement 36 causes the fan 34 to rotate with the armature shaft 33. The armature shaft 33 is preferably supported at both of its ends by self-aligning ball bearings consisting of the races 38,

39 and the balls 40 suitably mounted in a metal casing 41 located in a bore 42 in the end of the casing of the motor.

The bore 42 may be located in a metal partition 43, forming a part of the motor housing 20, and the end of the motor housing may be closed by the gear housing 44 which fits against the partition 43. Suitable slots 45 between the partition 43 and the main part of the motor housing 29 provide for the outward flow of the air caused by the fan 34.

The motor shaft preferably supports at its lower end a drive gear or pinion 46, which is adapted to drive the driven gear 47, which is mounted on a drive shaft 48. Drive shaft 48 has its upper end supported by anti-friction bearings comprising the outer race 49, balls 50, and inner race 51.

The member 52 comprises a cup leather for preventing the outward flow of the lubricant from the anti-friction bearings 49, 50, and 51 into the fan chamber. The upper end of the shaft 48 is slidably received in the inner race 51, and the shaft is rotatably and slidably supported by means of a lower anti-friction bearing comprising the outer race 53, balls 54, and inner race 55.

A spacing collar 56 is located between the gear 47 and inner race 55 on the shaft 48. A suitable oil seal or plate 57 is located at the upper side of the races 53, 55, the latter race fitting into the aperture in plate 57, and the outer race 53 being spun over the outer edge of plate 57. The outer race 53 is preferably slidably mounted in a metal sleeve 58 having an inwardly extending annular flange 59 at the top. A metal washer plate 60 is located in the sleeve 58 and engages the flange 59 for the purpose of providing a seat for a washer spring 61.

The washer spring 61 is illustrated in Fig. 5, and it comprises a metal plate of resilient steel or the like, of circular shape, and having a centrally located aperture 62, the aperture 62 being bordered by a plurality of resilient metal tongues 63 formed by slitting the metal outward radially at 64 and making an arcuate cut at 65. In one embodiment of my invention three of the spring tongues 63 are provided, their upper sides engaging the washer plate 60. The lower side of washer spring 61 engages the top of the race 53, and the washer spring 61 is compressed between the race 53 and the plate 60, thereby resiliently urging the race 53 and with it balls 54, outer race 55, and shaft 48, in a downward direction.

When axial force is impressed upon the shaft 48 in an upward direction, the spring washer 61 gives sufficiently to permit the shaft to move upward into the motor. Furthermore, the spring 61 serves as a spring support for the weight of the motor and removes from the grinding wheel the shock which would otherwise be caused by the weight of the motor on the shaft 48. The amount of unsprung weight bearing upon the grinding wheel is greatly diminished by resiliently mounting the shaft 48 for axial movement, and the shaft 48 is permitted to exert a vibratory action or to give impulses to the motor holder without transmitting shock which would be caused in case the motor were not sprung or resiliently supported with respect to the shaft 48.

The sleeve 58 may have a drive fit in a bore 66 in the lower end of the gear housing 44. Sleeve 58 is preferably threaded at its lower inner end 73

67 so as to receive the oil seal housing which comprises a threaded sleeve 68 having an inwardly extending annular flange 69.

The oil seal may comprise any suitable type 5 of oil seal, but in one embodiment of the invention consists of a hat-shaped leather having a cylindrical portion 70 and a radially outwardly extending flange 71. The cylindrical portion 70 of the leather is urged into engagement with the enlarged cylindrical portion 72 of the shaft by means of a coiled garter spring 73. A channel-shaped metal member 74, having inwardly extending annular flanges, houses the spring 73 and holds it into engagement with the leather 70.

10 The lower end of shaft 48 is provided with a threaded portion 75 for receiving the internally threaded driving knuckle 76 which has a threaded bore 77. At its lower end the driving knuckle 76 is provided with a non-circular portion 78 15 which may, for example, be hexagonal in form, and which has a flat lower end 79.

The flat end 79 is preferably beveled or chamfered at the corners 80 for the purpose of removing the sharp edges which would otherwise 20 wear, so that the physical characteristics of the end of the driving knuckle will remain the same.

The driving knuckle 76 is preferably made of special steel, and its action on the tool holder will be described in detail hereinafter. The motor driver 20 preferably operates at a speed within 30 the range of 13,000 R. P. M., which is considerably in excess of the speeds previously used by the drivers of the prior art, and the mechanism is capable of operation at this high speed 35 without the necessity for anti-friction bearings in the tool holder on account of the fact that there is no bearing load on the bearings of the tool holder except that which is involved by its guiding function.

40 The tool holder 21 preferably comprises a substantially cylindrical housing sleeve 81, which may serve as a handle, and which may be constructed of tubular fiber, "Bakelite", or other suitable material. The housing 81 is supported 45 by means of a supporting body or sleeve 82 of substantially cylindrical outer form, and provided with a radially outwardly extending flange 83 at its lower end adapted to be flush with the outer surface of the housing 81. Flange 83 is provided with an annular shoulder 84 adapted 50 to receive the sleeve or housing 81, and the supporting sleeve 82 is provided with a downwardly extending tubular portion 85, which is externally threaded for the purpose of receiving 55 the threaded hub 86 of the grinding wheel.

The grinding wheel 22 comprises a suitable 60 grinding stone of carborundum, emery, or other suitable material which is secured to the tubular hub 86 by means of cement 87. On its upper surface the grinding stone 22 has a cardboard annulus 88 cemented thereto, bearing the data regarding the size and angularity of the grinding stone. The upper surface 89 of the grinding stone is flat, and the periphery 90 is cylindrical. 65 The bottom 91 is preferably flat, and the working surface 92 is accurately frusto-conical in the case of valves for internal combustion engines, being dressed to frusto-conical form by means of the improved dressing tool described in a companion application, Serial No. 711,847, filed February 19, 1934.

70 The threads 75 of the drive shaft 48 and the threads on the sleeve 85 and hub 86 of the grinding wheel are, of course, opposite in direction to 75 the direction of rotation of these parts so that

the driving knuckle 76 and the grinding wheel 22 will both be driven home on their threaded supports by the action of the driving of the grinder.

5 The supporting sleeve 82 is provided with a cylindrical bore 93 extending throughout the major portion of the sleeve, and with an enlarged counterbore 94 at the top. The counterbore 94 is threaded at its upper end 95 for receiving the end of plug 96, which has a reduced threaded end 10 97 threaded into the bore 95. End plug 96 has an outwardly extending annular shoulder 98 which engages the end of sleeve 82 when it is threaded home therein, and it is also preferably 15 provided with the cylindrical surface 99 and an annular shoulder 100, the former being received in the housing 81, and the latter abutting against the end of the housing 81 for supporting the upper end of housing 81 on sleeve 82. Pins 101 driven through the housing 81 into bores 102 in 20 the reduced portion 97 of plug 96 firmly secure all of these parts together and prevent the threaded parts from becoming loose.

The end plug 96 is provided with a bore 103 25 extending through it, and the bore 103 emerges into an enlarged recess or counterbore 104. The intervening surface of the plug is frusto-conical at 105 to provide a suitable clearance between the central part of a spring washer 106 and the parts of the end plug 96.

30 The spring washer 106 is illustrated in greater detail in Fig. 7, and comprises a resilient, tempered steel member 106, circular in plan and provided with a centrally located aperture 107.

The spring washer 106 is provided with a plurality of radially extending rib formations 108, which in this case are located on two diameters at right angles to each other, for the purpose of further stiffening the spring, but in some embodiments of the invention the spring might be 40 made of sufficient stiffness without the ribs 108.

The ribs 108 preferably extend downward when the spring washer 106 is assembled with the tool holder 21 so as to increase the bearing surface against which the end of the driving 45 knuckle 76 engages over the surface which it would engage if the ribs projected upward. The spring washer 106 rests against an annular shoulder 109 at the base of the counterbore 104 and is clamped in place by a threaded member 50 110, the end of which engages the upper surface of the spring adjacent its periphery.

55 Threaded member 110 has its periphery threaded to be received in the threaded bore 104, and it also has its threads extending in such a direction that it will be driven home by the driving action of the motor driver. The threaded member 110 is provided with a centrally located aperture 111 which is preferably non-circular in form and slightly larger than the end 78 of the 60 driving knuckle 76 so as to permit the driving knuckle to tilt in the non-circular or hexagonal aperture 111, as shown in Fig. 2.

65 The clearance is more clearly illustrated in Fig. 6 and in Fig. 3, and the action and purpose 65 of this structure will further be described in detail.

The present tool holder presents a radical departure from the practices of the prior art with respect to bearings or tool holders in respect to 70 the materials employed. It has heretofore been customary to employ one hard metal and one soft metal in the two complementary parts of a trunnion and a bearing, on account of the lesser degree of wear which is brought about by the action 75

of the hard metal on the soft metal. In motor grinders of this type, however, the relatively soft metal, such as bronze or brass bearing metal, takes up the emery particles or carborundum particles or grindings, which become embedded in the soft metal, and this speedily wears down the other hard metal and renders the tool inaccurate.

In the present invention the upper end 22 of pilot 23 is preferably made of hardened steel, and the bore 93 of the supporting sleeve 82 is provided with a bearing sleeve 113, having an accurate cylindrical bore 114, and the bearing sleeve 113 is also preferably made of hardened steel.

Bearing sleeve 113 may be a drive fit in the supporting sleeve 82, and it should fit the upper end of the pilot with a slight clearance sufficient to permit it to rotate freely, but with sufficient accuracy to prevent any wobbling or other movement.

It is found that when a slight amount of lubricant is used on these two hard contacting surfaces the device may be driven at very high speeds, such as, for example, 13,000 R. P. M., without appreciable wear, as neither of the hard surfaces takes up the grinding wheel particles in the manner that took place in the soft bearing metals of the prior art. The pilot and bore 93 are fitted accurately by a lapping operation.

Therefore, the tool holder may be used for a long period of time and retains its accuracy and fit with respect to the pilot, and it is not necessary to utilize anti-friction bearings which involve other moving parts, but the present device can be made far more accurate, due to the fact that it uses two complementary cylindrical parts which may be accurately ground to proper size and fit.

Referring now to Fig. 4, it will be evident that the drive shaft 48 may be moved inward and outward with respect to the motor 20 by virtue of the sliding arrangement of its bearings in their sockets and the resilient action of the spring 61 which urges the shaft outward. This spring action eliminates shocks on the grinding wheel which might otherwise be caused by the unsprung weight of the motor, and the spring 106 in the tool holder has a similar action in preventing such heavy shock to the grinding wheel that the grinding wheel would break.

Referring to Fig. 1, this is a side elevational view of the assembly with the driver in the middle or vertical position, which the driver generally assumes when the operator begins his operations. While the driver is operating at a high speed, however, the operator sways the handle 115 back and forth through a relatively small distance, moving the driving motor 20 angularly with respect to its driving knuckle 76 as a center. This swinging movement of the motor results in a different action on the grinding wheel 22, and effects a dispersion of the cuttings and constant cleaning of the grinding wheel, as follows.

Referring to Fig. 3, it will be observed that the non-circular or hexagonal end 78 of the driving knuckle is there shown at an angle with the end plug 96 or at an angle to the axis of the pilot 23 and tool holder 21. As the hexagonal part 78 rotates there is an axial movement of this hexagonal part, due to the distance between the spring 106 and the successive corners 116, 117, 118, and 119 of the hexagonal part. In other words, at the instant shown the corner 116 of the driving knuckle 78 is in engagement with the spring 106, but as the corner 118 rotates downward toward

the position where it will engage the spring 106 there is an axial movement of the drive shaft downward which is equal to the distance X shown in Fig. 3. Thus the use of a non-circular driving member disposed at an angle causes the drive shaft to give a number of downward impulses to the tool holder, the shock of which is, however, partially absorbed by the spring 106, and the shock of the motor weight is not transmitted to the tool holder on account of the fact that the motor is spring supported by means of the spring 61.

This vertical impulse action of the drive shaft on the tool holder produces variations in pressure on the grinding wheel 22 as it grinds the seat 24. Furthermore, the pilot stem 23 is a relatively slender and resilient metal member, and the tilt of the drive shaft 48 and driving knuckle 76 gives these periodic impulses a lateral component which tends to cause the tool holder to vibrate with the pilot stem in a lateral direction, somewhat like the vibration of a tuning fork. Thus the tool holder is subjected to vertical impulses and/or vibrations and to lateral impulses and/or vibrations, and the grinding wheel is subjected to variations in vertical pressure and variations in angular movement about the lower end of the pilot as a center, which permits the grinding wheel to lift slightly from its working surface and disperse the cuttings.

The exact theory on which the action is based cannot be certainly determined, but it is positively known that the swaying action of the motor driver with the structure of the pilot, tool holder and shock absorbing springs as described results in a complete dispersion of the cuttings while the grinder is operating, and the grinder is capable of producing a substantially mirror-like valve surface without any grooves or other irregularities and without producing any noticeable wear on the grinding stone. All of this may be done at a very high speed, the high speed aiding the smooth action of the grinder and subjecting the grinder to high frequency vibration, as well as increasing the speed at which the work may be done.

Assuming a rotary speed of 13,000 R. P. M., using a hexagonal driving knuckle, each corner of the grinding knuckle will produce one complete vertical oscillation or variation in pressure or lateral oscillation on the pilot because the impulse which is given to the tool holder by the corners of the hexagonal driving knuckle takes place between the flat portion of the driving knuckle and each corner. The frequency of vibration would, therefore, be six times 13,000, or in the range of 78,000 complete vibrations per minute.

Referring to Fig. 8, this is a modified assembly for the purpose of illustrating the fact that the present tool holder may be employed with an ordinary drill motor. The assembly here includes the same pilot and tool holder 21 as set up in Fig. 1, but the ordinary drill motor 120, which is provided with a chuck 121, is connected to the tool holder 21 by means of flexible shaft 122, having at its lower end a driving knuckle end 78 of the same shape as previously described.

In this case the drill motor operates at about 2,000 R. P. M., and the work is accomplished much more slowly and in a different manner, due to the different structure of the assembly, but the present tool holder is shown to be capable of use with ordinary drill motors as well, which places these tools within the means of a large number of

users who cannot afford to buy a special motor driver for the grinder.

It should also be pointed out that the grinder is preferably supplied with a rough or coarse stone and with a relatively fine finishing stone, in order to secure the best possible finish, but a mirror-like surface of extremely smooth and uniform characteristics can be produced on a valve seat with the present grinder, even by the use of a

10 relatively coarse stone.

The mode of operation of the present apparatus and the method of reconstructing valve seats according to the present invention may be described as follows: The grinding stone is first 15 dressed to an accurate frusto-conical surface of predetermined angularity, determined by the angularity of the valve seat in question. The valve stem pilot is then fixedly secured in the valve stem guide by shoving the tapered portion of 20 the pilot down into the guide until the pilot is fixed therein. The tool holder bearing the grinding stone is then slidably and rotatably mounted on the guide, and the motor driver is held above with its driving knuckle, having the non-circular 25 end in the non-circular socket of the tool holder.

It is not necessary to exert any pressure on the motor driver, but, on the contrary, a very light pressure is desirable, such as that exerted by the weight of the motor itself. The motor may 30 then be turned on and the grinding stone and tool holder rotated at a high speed of approximately 13,000 R. P. M., while the handle of the motor is oscillated back and forth through a small arc of from fifteen to thirty degrees, more or less, 35 depending upon the range of motion permitted by the clearance between the non-circular socket and the non-circular end of the drive shaft.

This high frequency vibration results in the dispersion of the cuttings and produces a mirror-like seat without any substantial effect on the 40 grinding stone.

The method of grinding valve seats may be described as rotating a grinding stone in full contact with a valve seat, without subjecting the 45 grinding stone to periodic vibrations, varying the pressure and/or area of contact of the stone by angular oscillations of the stone in such manner as to constantly disperse the cuttings, and prevent clogging or loading of the stone.

50 It will thus be observed that I have invented an improved valve seat grinder, the structure of which is considerably simplified over the devices of the prior art, inasmuch as it does not require any complicated driving mechanism for both rotating and revolving the stone, and yet the device effects a dispersion of the cuttings, constant cleaning of the stone, and produces a mirror-like finish on the valve seat, which could not be done with the full contact stones of the prior art.

60 The spring action of the resiliently mounted drive shaft prevents shocks to the stone by means of the mass of the motor and the periodic impulses transmitted to the tool holder and stone by means of the resiliently mounted drive shaft 65 produces a vibratory action of the stone, which slightly lifts the stone from its seat periodically as the grinding progresses and permits the cuttings to be thrown off centrifugally, this action being also aided by the air currents caused by the 70 rotating stone.

The present grinding apparatus is so simple that it may be manufactured at a much lower cost than the complicated devices of the prior art, particularly the eccentric type of grinders, and 75 this grinder may be manufactured at a cost which

is within the means of a vast number of purchasers.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I 10 claim is new and desire to secure by Letters Patent of the United States, is:

1. In a valve seat grinder, the combination of a valve stem pilot with a tool holder adapted to be slidably and rotatably mounted on said pilot 15 and a grinding wheel carried by said tool holder, a driving shaft for said tool holder, driving means for said shaft, a universal connection between said tool holder and said driving shaft, and a spring interposed between said driving shaft and said 20 tool holder comprising a substantially flat and resilient metal member supported at its outer edge and located in a socket in the end of said tool holder.

2. In a valve seat grinding apparatus, the combination of a pilot stem adapted to be centered with respect to a valve stem guide, a tool holder slidably and rotatably mounted on said pilot stem, a grinding wheel mounted to rotate with said tool 25 holder, a motor driver, non-circular complementary parts on said motor driver and tool holder whereby the tool holder is driven by said motor driver, resilient means interposed between said motor driver and tool holder, said non-circular 30 parts having suitable clearance whereby the motor driver may be tilted and the non-circular parts on the motor caused to transmit periodic impulses to the tool holder for the purpose of dispersing the cuttings.

3. In a valve seat grinding apparatus, the combination of a pilot stem adapted to be centered with respect to a valve stem guide, a tool holder slidably and rotatably mounted on said pilot stem, a grinding wheel mounted to rotate with said tool holder, a motor driver, non-circular 45 complementary parts on said motor driver and tool holder whereby the tool holder is driven by said motor driver, said non-circular parts having suitable clearance whereby the motor driver may be tilted and the non-circular parts on the motor 50 caused to transmit periodic impulses to the tool holder for the purpose of dispersing the cuttings, and resilient means interposed between the motor and the tool holder for absorbing the direct shocks of said impulses on the grinding wheel.

4. In a valve seat grinding apparatus, the combination of a pilot stem adapted to be centered with respect to a valve stem guide, a tool holder slidably and rotatably mounted on said pilot stem, a grinding wheel mounted to rotate with said tool holder, a motor driver, non-circular complementary parts on said motor driver and tool holder whereby the tool holder is driven by said motor driver, resilient means interposed between said motor driver and tool holder, said non-circular 65 parts having suitable clearance whereby the motor driver may be tilted and the non-circular parts on the motor caused to transmit periodic impulses to the tool holder for the purpose of dispersing the cuttings, said motor having its drive shaft resiliently mounted for axial movement whereby the weight of the motor is spring mounted with respect to the grinding wheel.

5. In a tool holder for valve seat grinding apparatus, the combination of a supporting sleeve 75

- provided with an outwardly projecting flange adjacent one end, a threaded extension beyond said flange, a cylindrical part on the other side of said flange for engaging a handle sleeve, a threaded plug mounted in the opposite end of said supporting sleeve and having a cylindrical surface for engaging in said handle sleeve, said plug having an outer cylindrical surface flush with the cylindrical surface of said handle sleeve and means for securing said plug to said supporting sleeve to retain said assembly in permanent assembly.
6. In a tool holder for valve seat grinding apparatus, the combination of a supporting sleeve provided with an outwardly projecting flange adjacent one end, a threaded extension beyond said flange, a cylindrical part on the other side of said flange for engaging a handle sleeve, a threaded plug mounted in the opposite end of said supporting sleeve and having a cylindrical surface for engaging in said handle sleeve, said plug having an outer cylindrical surface flush with the cylindrical surface of said handle sleeve, said end plug being formed with a non-circular socket, and a spring located in said non-circular socket and adapted to engage the end of a non-circular drive shaft for driving said tool holder to absorb the shocks caused by said non-circular drive shaft.
7. In a valve seat grinder, the combination of a valve stem pilot with a tool holder slidably and rotatably mounted on said pilot, said tool holder having a non-circular socket, a drive shaft having a complementary non-circular part adapted to be received in said socket, resilient means mounted in the base of said socket for engaging said drive shaft, said socket having sufficient clearance so that the drive shaft may be tilted therein and the successive corners of the drive shaft may transmit axial impulses to the tool holder as the drive shaft rotates in tilted position.
8. In a valve seat grinder, the combination of a valve stem pilot with a tool holder slidably and rotatably mounted on said pilot, said tool holder having a non-circular socket, a drive shaft having a complementary non-circular part adapted to be received in said socket, resilient means mounted in the base of said socket for engaging said drive shaft, said socket having sufficient clearance so that the drive shaft may be tilted therein and the successive corners of the drive shaft may transmit axial impulses to the tool holder as the drive shaft rotates in tilted position, said pilot being resilient, whereby the horizontal component of the impulses transmitted to the tool holder by said tilted drive shaft causes lateral vibration of the tool holder and pilot to effect a dispersion of the cuttings.
9. In an apparatus for grinding valve seats, the combination of a pilot stem adapted to be centered with respect to a valve stem guide, a tool holder slidably and rotatably mounted on said pilot stem, a grinding wheel mounted to rotate with said tool holder, resilient means carried by said tool holder in a socket for receiving a drive shaft, a motor driver comprising a motor having a field and an armature shaft, an armature and a drive pinion, a separate drive shaft protruding from said motor driver and engaging in said socket against said resilient means, said separate drive shaft having a gear for engaging said pinion and being slidably mounted with respect to said motor; and resilient

means for urging said separate drive shaft outward with respect to the motor whereby the said separate drive shaft may oscillate with respect to the motor and transmit vibrations to a tool holder without vibrating the motor.

10. In an apparatus for grinding valve seats, the combination of a pilot stem adapted to be centered with respect to a valve stem guide, a tool holder slidably and rotatably mounted on said pilot stem, a grinding wheel mounted to rotate with said tool holder, resilient means carried by said tool holder in a socket for receiving a drive shaft, a motor driver comprising a motor having a field and an armature shaft, an armature and a drive pinion, a separate drive shaft protruding from said motor driver and engaging in said socket against said resilient means, said separate drive shaft having a gear for engaging said pinion and being slidably mounted with respect to said motor, and resilient means for urging said separate drive shaft outward with respect to the motor whereby the said separate drive shaft may oscillate with respect to the motor and transmit vibrations to a tool holder without vibrating the motor said separate shaft being rotatably mounted in anti-friction bearings and said anti-friction bearings being arranged to permit reciprocation of the drive shaft with respect to the motor.

11. In a tool holder for valve seat grinders, the combination of a tubular metal member having an internal bore adapted to fit upon a valve stem pilot, said tubular metal member having a threaded end for receiving a threaded hub of a grinding wheel, and having a non-circular socket formed at its opposite end, and a spring comprising a resilient flat metal member having its outer edge secured to said tubular metal member in said socket and adapted at its central portion to engage a non-circular driving member when inserted in said socket.

12. In a driver for valve seat grinders, the combination of a motor provided with a casing, a gear casing carried by one end of said motor casing, said motor having an armature with a shaft projecting into said gear casing, a pinion on said armature shaft, a drive shaft projecting from said gear casing and having a non-circular drive shaft, said drive shaft having a gear engaging said pinion, bearings for said drive shaft in said gear housing permitting the sliding movement of said drive shaft in the direction of its axis, and resilient means in said gear casing for urging said shaft outward whereby the motor driver is adapted to be resiliently supported by said spring when resting on a driven member by means of said drive shaft.

13. The method of dressing valve seats of internal combustion engines which comprises rotating a grinding wheel in substantially full contact with a valve seat, simultaneously subjecting the grinding wheel to periodic vibratory impulses in the direction toward the valve seat and subjecting the grinding wheel to lateral components of impulses tending alternately to lift one or the other side of the grinding wheel and to depress the opposite side of the grinding wheel to cause the grinding wheel to lift sufficiently from the seat to disperse the grindings.
